ROADWAY GATE

Filed Aug. 30, 1920

Inventor

By his Attorney Jacob Hansen
Emerson R. Howell.

UNITED STATES PATENT OFFICE.

JACOB HARSEN, OF NEW YORK, N. Y.

ROADWAY GATE.

Application filed August 30, 1920. Serial No. 406,842.

To all whom it may concern:

Be it known that I, JACOB HARSEN, a citizen of the United States, residing at New York city, New York, have invented certain new and useful Improvements in Roadway Gates, of which the following is a clear, full, and exact description.

My invention relates to gates and more especially to those gates adapted to be moved across a roadway to temporarily prevent passage of traffic, more especially vehicles, and an object of my invention is to improve the construction of gates of this character whereby they are rendered safer.

Other objects and important features will become apparent from the following detailed description and claims when taken in connection with the accompanying drawings, in which—

Fig. 1 is a side elevation of a portion of a gate showing electrically controlled means therefor;

Fig. 2 is a similar view showing pneumatic means for controlling the gate, this view also showing the outer end of the gate engaged by a suitable keeper;

Fig. 3 is a view similar to Fig. 2 but showing the parts in a different position;

Fig. 4 is a broken plan view showing the manner of connecting the cable to the gate structure; and

Fig. 5 is a detail of the keeper.

It has been customary to provide vertically swinging gates to temporarily block traffic at roadways, especially at railway crossings, and these gates have usually comprised one or more pivoted members adapted to be operated by power means, usually pneumatic, the gates being balanced so that they may rather easily be swung from closed to open position, or vice versa. When in closed position, the gate merely extends across the roadway, but if a vehicle runs into such a gate, there is great danger of the gate lifting and permitting the vehicle to pass under it. My invention is directed more particularly to a gate structure in which the gate is locked in closed position so that it would be almost impossible for a vehicle to break through, even if it should accidentally run into the gate. It is obvious that the kind of power employed is immaterial, and in the particular embodiment of my invention I have shown a gate operated both by electrical and by pneumatic power.

Referring to the drawings, Fig. 1 in-

dicates my improved gate operated electrically. In this form of device, a support 1 is provided which may form the fulcrum for the gate and may also provide a housing for the motor 2, which motor is adapted to move the gate by means of a beveled pinion 3 connected to the motor shaft 4, said pinion engaging a beveled gear 5 mounted on a shaft 6, which carries a worm 7 engaging a sector 8 forming part of, or rigidly attached to the gate 9, said gate pivoting about a fulcrum 10. The motor is adapted to be run in either direction and, as will be readily seen, movement thereof in one direction will act to move the gate from closed position indicated in Fig. 1 to open position. The motor is supplied with current from line wires 11 and 12 under control of a switch indicated at 13, the circuits being indicated diagrammatically in the figure.

When the switch 13 is in full line position, which is that shown in Fig. 1, current will flow through the wire 12 to the wire 14, through the field magnet of the motor, 80 through wire 15 and back through the switch to the wire 11. Current will also flow through the wire 16 to the motor armature, returning through the wire 17 to the other side of the line.

In order to positively lock the gate in closed position, I provide a keeper 18, Fig. 2, which may be secured to a post 19, or if two gates are provided, the keeper 18 will be secured to the other gate. I also provide a lock which comprises a hook 20 adapted to pass through the keeper, said hook having an opening in its lower end through which a bolt 21 may extend so as to embrace the keeper between it and the hook when the gate is closed, so that when the lock is in operative position it will be impossible to raise the gate until the bolt is again released. Preferably I control the bolt automatically in such a manner that it is moved to locking position as the gate reaches closed position, and I also preferably provide means whereby the bolt is released concomitantly with the starting of the opening movement of the gate.

In order to control the lock in the device illustrated in Fig. 1, wherein the gate is shown as electrically controlled, the bolt 21 is connected to the core 22 of a solenoid 23. Mounted in alignment with this solenoid 110 23 is a second solenoid 24, the core 22 being common to both solenoids. As the gate

moves to closed position, a contact 25 on the sector 8 makes contact at 26 so that a circuit is closed through the solenoid 22, the circuit flowing from the wire 12, through 5 the wire 14, to the point 27. From this point the current flows through the wire 28 and the wire 29 to the contact 25, to the contact 26, wire 30, through solenoid 22, returning to the other side of the line through the wire 31. 10 Energization of the solenoid 22 results in shooting the bolt to position to lock the gate and this occurs just as the gate reaches closed position, the hook 20 having passed through the keeper 18, as illustrated in Fig. 15 2. When the switch 13 is moved to dotted line position shown in Fig. 1, so as to reverse the direction of current passing through the motor, current will also be supplied to the solenoid 24, and under these 20 conditions current will flow from the wire 12 to the wire 32, to the point 33, through wire 34, to solenoid 24; returning through wire 35, to the point 36, through the switch, to point 37 and back to the other side of the line. The bolt will therefore be released due to energization of the solenoid 24 concomitantly with the supplying of current 25 to the motor to raise the gate.

In the form of device shown in Figs. 2 and 30 3, the gate is operated by air pressure, and in this form of device I have also utilized the air pressure to operate the bolt, both to lock and to unlock the same. In this form of device, a fluid pressure cylinder 38, which 35 may be of usual construction, may be provided within the housing 1, said cylinder having a piston which may be connected with a rack 39 engaging a toothed wheel 40 carried by the gate, which is pivoted 40 at 41. Fluid pressure is supplied to the cylinder 38 by means of pipes 42 and 43. These pipes may lead to an air pump or to any suitable source of fluid supply. In 45 Fig. 2 the parts are shown in the position they occupy when the gate is closed and locked. With the parts in this position, therefore, the first thing to be done is to release the lock, and this is accomplished by admitting fluid pressure to the right 50 side of a fluid pressure cylinder 44 mounted on the gate, said cylinder having a piston 45 to which is connected the bolt 21. An air supply pipe 46 leads from the cylinder on the right side of the piston to a dia- 55 phragmed chamber 47. The pipe 43 also leads into this chamber and opening from it is a pipe 48 supplying fluid pressure to the cylinder 38 above the piston. Therefore, 60 when air or other fluid is admitted to the pipe 43, it passes into the diaphragm chamber 47 and thence to the pipes 46 and 48, actuating the bolt 21 and also supplying fluid pressure to the cylinder 38 to move the gate to open position.

In order that the bolt may be moved to

locking position as the gate reaches closed position, I provide means for controlling the fluid pressure to the other side of the cylinder 44, said controlling means consisting of a valve 49 having a right-angled opening 50 therein. As the gate moves from closed position to open position, a link 51 connected to the gate at 52 operates a lever 53 through pin-and-shot connections 54—55, lever 53 being connected to the valve 49 so that said valve is moved from the position shown in Fig. 2 to that shown in Fig. 3 when the end of the slot 55 engages the pin 54 near the end of the movement of the gate to opened position. When the valve is in the position indicated in Fig. 3, passageway from the chamber 56 to a pipe 57 leading to the other end of the cylinder 44 is closed. When it is desired to close the gate, fluid pressure is admitted through the pipe 42 and enters the chamber 56. A pipe 58 leads from the chamber 56 to the lower portion of the cylinder 38 so that when the pipe 42 is opened, fluid pressure enters the underside of the piston in the cylinder 38 raising the same and causing the gate to lower. Since the passageway to the pipe 57 is closed by the valve 49, as indicated in Fig. 3, no fluid pressure will be supplied at this time to the cylinder 44, and therefore the bolt will remain inoperative. 95 However, as the gate reaches closed position, the pin 52 bears on the cam edge 59 of a cam lever 60, said lever at its other end engaging a pin 61 on the lever 53, this engagement resulting in the rocking of said lever and moving the valve 49 from the position shown in Fig. 3 to that shown in Fig. 2, thereby permitting the fluid pressure in the chamber 56 to flow through the pipe 57 and into the cylinder 44 at its left-hand end, as shown in Fig. 2. The bolt is then shot out to the position shown in Fig. 2, thereby locking the gate to the keeper. In both constructions described, the bolt is moved to locking position as the gate reaches closed position, and as the power is applied to move the gate, the bolt is automatically released. 100 Since the framework of gates of this general character is made comparatively light and would not be sufficiently strong to resist breaking when in locked position if struck by a vehicle at this time, in order to strengthen the gate and to prevent a vehicle from breaking it and passing through the gate in case it should accidentally strike it, I provide a cable indicated at 63. This cable has its ends fastened into screw eyes 64 which screw-eyes are connected to a cross piece 65 forming the end of a sleeve member 66, this member engaging over an enlarged portion 67 connected to the bolt. A spring 68, Fig. 1, is interposed between the inner end of the sleeve and the end of the member 67 so that the sleeve has limited 110 sliding movement. A suitable stop 69 may 115

be provided, against which the ends of the screw eyes 64 bear under expansive action of the spring. The cable is fastened at its ends to the screw eyes as already described, 5 and is looped around the end of the hook, as shown in Fig. 4 and runs longitudinally of the gate. This cable is made of sufficiently strong wire to resist any strain which it is likely to be called upon to withstand.

10 While I have shown at least two practical embodiments of my invention, it is of course to be understood that various other forms may be used within the spirit of the invention and that some of the parts may 15 be used without others.

What I claim as new is:

1. In a gate structure, the combination with a gate, of power means for moving the gate, a lock for said gate including a bolt, a 20 fluid pressure cylinder into which said bolt enters, a piston in said cylinder connected with the bolt, means for admitting fluid pressure to one side of said piston to move the bolt to unlocking position concomitantly 25 with the application of the power means to open the gate, and means controlled by movement of the gate to closed position for admitting fluid pressure to the other side of said piston to actuate said bolt to locking 30 position.

2. In a gate structure, the combination with a gate, of a lock for said gate including a bolt, a fluid pressure cylinder into 35 which said bolt enters, a piston in said cylinder connected with the bolt, a source of fluid pressure, a valve connecting said source with one side of said piston when said valve is in one position and cutting off said supply

when in another position, and means on the gate for controlling said valve. 40

3. In a gate structure, the combination with a gate, of a lock for said gate including a bolt, a fluid pressure cylinder into which said bolt enters, a piston in said cylinder connected with the bolt, a source of fluid pressure, a valve connecting said source with one side of said piston when said valve is in one position and cutting off said supply when in another position, and means on the gate for opening said valve as said gate 45 reaches closed position. 50

4. In a gate structure, the combination with a gate, of a lock for said gate including a bolt, a fluid pressure cylinder into which 55 said bolt enters, a piston in said cylinder connected with the bolt, a source of fluid pressure, a valve connecting said source with one side of said piston when said valve is in one position and cutting off said supply when in another position, and means on 60 the gate for opening said valve as the gate reaches closed position and for closing said valve as the gate opens.

5. In a gate structure, the combination with a gate, of a locking bolt therefor, extending longitudinally of the gate, a guide for said bolt, a cable looped around one end of said gate and arranged longitudinally thereof, and means for resiliently supporting the ends of said cable for limited movement, said supporting means comprising a sleeve mounted for sliding movement on 65 said bolt guide. 70

Signed at New York city, N. Y., this 1st day of June, 1920.

JACOB HARSEN.
